MEANS FOR SUPPORTING AND DELIVERING
HAIRPINS AND THE LIKEOtto Klotz, Chicago, Ill., assignor of one-third to
Milton Klotz, and one-third to Jerry Kramer,
both of Chicago, Ill.

Application October 5, 1939, Serial No. 298,087

11 Claims. (Cl. 312—83)

This invention relates to means for supporting and delivering hairpins and the like and it has for its object the provision of a new and improved form and arrangement of parts by which a series of hooked members such as hairpins are readily available for use, one at a time, by hairdressers, for example. An operator in a beauty parlor often requires a very considerable number of hairpins and it is highly important, from an efficiency and speed standpoint, that the pins be quickly and easily available one after another with a minimum of attention on the part of the operator so as to enable the operator to give his undivided attention to the manipulation and arrangement of the hair.

For meeting these requirements, I have provided an improved arrangement of mechanism adapted to support a large number of hairpins and arranged so that the removal of one pin from its final support position serves to permit the next adjacent pin on the support to move forwardly into a similar final support position with its leg portions hanging free and clear so as to be readily and quickly grasped by an operator. My preferred arrangement comprises an inclined supporting bar upon which hairpins are to be arranged preliminarily, together with a movably mounted lever at the lower portion of the supporting bar so positioned that the removal of the pin from the lower end of the bar serves by a camming action to give the lever an operative stroke for releasing the next adjacent hairpin from engagement with a retainer by which the supply of pins is held in a slightly elevated position on the supporting bar. It has been one of the objects of this invention to provide an improved arrangement of elements comprising a grooved part adapted to be moved by the lever into position for receiving a single hairpin into the groove so that upon the return movement of the lever such engaged pin is moved downwardly with the lever away from the supply of pins on the supporting bar.

It is another object of this invention to improve devices of this type in sundry details hereinafter pointed out. The preferred means by which the several objects of the invention have been attained are illustrated in the accompanying drawing, in which

Fig. 1 is a top plan view of the preferred form of the improved device.

Fig. 2 is a side elevational view of the device.

Fig. 3 is a side elevational view of a portion of the device with the controlling lever in changed position; and

Fig. 4 is a cross sectional view taken substantially at the line 4—4 of Fig. 2.

Referring now to the several figures of the drawing, in which corresponding parts are indicated by the same reference characters, 10 indicates a base member of wood, or the like, having an auxiliary base member 11 preferably of sheet metal hingedly connected therewith at 12. Upon the top face of the auxiliary base member 11, a supporting member 13 in the form of a sheet of metal is secured on edge, being held rigidly in position with respect to the plate 11 in the arrangement shown by means of angle bars 14 and 15, as is best shown in Fig. 1. As is clearly shown in Fig. 2, the upper edge portion of plate 13 is obliquely disposed so as to provide an inclined slide bar portion 16 adapted to slidably support a plurality of hooked members such as hairpins 17 of ordinary form, such hairpins being supported in straddling relation to the plate. At the rear edge of the body portion of plate 13, an extension portion 18 is provided of triangular form tapering to a point at 19. As is best shown in Fig. 1, the portion 18 in the arrangement shown is bent around toward the front so as to cause the extreme end portion of the extension 18 to extend forwardly. At the opposite edge of the plate 13, it is provided with a forwardly projecting extension 20 the upper edge portion of which is substantially parallel with the slide bar portion 16 of the body of the plate, being arranged at a slightly lower level.

At opposite sides of the plate 13 in conveniently spaced relation thereto, I have provided standards 21 and 22 provided at their upper ends with horizontally disposed pins 23 and 24, respectively, extending toward the plate 13. Upon such pins, I have pivotally mounted a lever or arm 25 the rear end portion of which is in the form of a yoke comprising legs 26 and 27, by which the lever is movably mounted in position. In the arrangement shown, the lever 25 and the connected mounting legs 26 and 27 are formed integrally out of sheet metal, the ends of the legs 26 and 27 being twisted through 90° for expediting their connection with the pins 23 and 24. As is clearly shown in Fig. 2, the lever 25 is bent downwardly somewhat sharply immediately in front of the crossbar portion 28 of the yoke so as to bring the face of the lever 25 closely adjacent to the shoulder at the lower end of the slide bar portion 16 of the plate 13. At a still further advanced point, the lever 25 is bent downwardly and then upwardly to provide a bowed portion at 29, such bowed portion being 55

provided with a slot 30 adapted to receive the end of the forwardly projecting slide bar 20 therein, as is clearly indicated in Fig. 2. In the position of the parts as shown in Fig. 2 the lever 25 is supported by engagement with the forwardly extending plate portion 20.

At the portion of the lever 25 directly opposite to the shoulder at the lower end of the slide bar portion 16, I have provided a bearing plate 31 the rear edge of which stands normally in close proximity to the shoulder at the lower end of the slide bar portion 16. The arrangement is such that when the lever 25 stands in the position as shown in Fig. 2, a series of hooked parts 17 such as hairpins 17 are held in position on the slide bar 16, the bearing plate 31 serving to prevent the pins from sliding off the lower end of the slide bar. When, however, the lever 25 is raised to the position as shown in Fig. 3, a recess 32 in the form of a notch in the edge of the bearing plate 31 is brought into position opposite the lowermost hairpin 17 on the slide bar 16 so as to permit such lowermost pin to enter the slot 32. The arrangement is such that upon the next 25 succeeding downward movement of the lever 25 the single one of the pins 17 engaging the notch 32 is moved downwardly with the lever so as to be freed from the lower end of the slide bar 16. As soon as the lever 25 reaches its normal lowered position as shown in Fig. 2, the pin is freed in turn from the bearing plate 31 and is permitted to drop into engagement with the inclined upper face of the extension 20, the downward movement of such pin being stopped when the 35 pin reaches the bowed portion 29 of the lever.

Upon the upper ends of the standards 21 and 22, I have rigidly mounted in position a heavy yoke 33 the cross bar portion of which is rigidly connected with a guard bar 34 which is held in 40 slightly spaced relation to the slide bar 16 for preventing the hairpins 17 from becoming disarranged upon the slide bar.

With the parts in position as shown in Fig. 2, a considerable number of hairpins 17 are placed 45 in position upon the upper end portion of the slide bar 16, the inclination of the slide bar being such that the pins are adapted to slide downwardly between the slide bar 16 and the guard 34 until they are brought into engagement with the bearing plate 31. In order to control, more or less, the pressure of the pins against the bearing plate 31, I have provided a set screw 35, mounted 50 adjustably in the auxiliary base plate 11, for enabling an operator to change the angle of the slide bar 16 as may be required. In the arrangement shown in Fig. 2, the auxiliary base plate 11 is shown in slightly raised position by reason of the set screw 35 being in operative engagement 55 with the base 10. It will be appreciated that the angle of inclination of the slide bar 16 can be decreased by turning the set screw 35 in the direction for raising the auxiliary base plate 11 still further. The pressure of the hairpins 17 upon the bearing plate 31 is still further limited by 60 the curvature of the extension 18 to one side and then forwardly, it being appreciated that the presence of this return bend in the slide bar serves to have a braking effect with respect to the downward movement of the pins upon the slide bar. 65

With a plurality of pins 17 in position upon the device as shown in Fig. 2, with a single pin 17 in position upon the forwardly extending portion 20, the device is in condition for normal use. When an operator desires a pin, the lowermost 70 pin 17 adjacent to the bowed portion 29 of the

lever is, of course, readily available, since it hangs with the major portion of its length clear and free below the projecting portion 20 and the lever 25 and well in advance of the body portion of the plate 13. The arrangement is such that the single pin 17 on the extension 20 can be drawn very quickly and easily downwardly and toward the left in Fig. 2 out of position on the device, such downward movement of the pin 17 serving by a camming action on the loop 29 to move the lever 25 upwardly into the position as shown in Fig. 3 so as to release the next adjacent pin 17 which moves promptly on the next succeeding downward stroke of the lever 25 into position on the extension 20 to be stopped by said lever as 10 shown in Fig. 2. The arrangement is such that as many pins as are required can be moved one at a time with no delay whatever and with no attention whatever on the part of the operator.

While the form of device as shown in the drawing and as above described is preferred, it is to be understood that the invention is not limited to the form and arrangement shown and described except so far as the claims may be so limited, since changes might well be made in the form 25 and arrangement of the parts without departing from the spirit of the invention.

I claim:

1. A device for supporting and delivering hairpins and the like, comprising in combination a 30 metal plate on edge for slidably supporting a plurality of hooked parts engaging the plate at their hooked portions and held so as normally to escape from the support one at a time, and a member movable adjacent to the point of escape 35 of said hooked parts from said support adapted normally to prevent a hooked part from sliding off the support and provided with a recess in its face adapted by engagement with a single one of said hooked parts upon movement of said member to carry said hooked part off the supporting means.

2. A device for supporting and delivering hairpins and the like, comprising in combination a supporting member in inclined position for supporting a hooked part so as to slide downwardly therealong and off at its lower end, and a vertically movable member having a transversely disposed recess in its face adapted in normal position to hold said hooked part from movement off the lower end of the supporting member and movable upwardly into position to receive said hooked part into said recess for movement downwardly off the supporting member upon the next subsequent downward stroke of said vertically 55 movable member.

3. A device for supporting and delivering hairpins and the like, comprising in combination a slide bar for supporting a plurality of hooked parts so as normally to escape from one end of 60 the bar one at a time, a lever pivotally mounted in position with a face portion normally standing opposite to the end of the bar for preventing the escape of the hooked parts from the bar and provided with a recess adapted upon an operative movement of the lever to receive a hooked part therein and release it from the bar, an auxiliary support to which a hooked part passes when released from said bar, and means actuated by removal of a hooked part from said auxiliary 65 support to give said lever an operative stroke.

4. A device for supporting and delivering hairpins and the like, comprising in combination a slide bar in inclined position for supporting a plurality of hooked parts so as to slide downward- 75

ly therealong and off at the lower end of the bar, and a lever pivotally mounted in position with a face portion normally standing opposite to the lower end of the bar adapted normally to prevent the escape of the hooked parts from the bar and having a transverse groove in said face portion which in the movement of the lever is carried toward and from the end of the bar so as to receive a hooked part into the groove at one position of the lever and to release the hooked part from the bar upon the subsequent movement of the lever.

5. A device for supporting and delivering hairpins and the like, comprising in combination a supporting member in inclined position for supporting a plurality of hooked parts so as to slide downwardly therealong and off at the lower end of the member, means for adjusting the angle of inclination of said supporting member, and a 10 retainer movable adjacent to the lower end of said supporting member adapted in normal position to prevent a hooked part from sliding off the support and provided with a recess adapted in a raised position of the retainer to receive therein the lowermost hooked part on the support for moving said hooked part downwardly therewith for escape from said supporting member.

6. A device for supporting and delivering hairpins and the like, comprising in combination means for slidably supporting a plurality of hooked parts so as normally to escape from the support one at a time, a member movable adjacent to the point of escape of said hooked parts from said support adapted normally to prevent 15 a hooked part from sliding off the support and provided with a recess in its face adapted by engagement with a single one of said hooked parts upon movement of said member to carry said hooked part off the supporting means, and means actuated by the removal of one of said hooked parts from the device for giving said movable member an operative stroke for releasing another hooked part from said supporting means.

7. A device for supporting and delivering hairpins and the like, comprising in combination a slide bar for supporting a plurality of hooked parts so as normally to escape from one end of the bar one at a time, a lever pivotally mounted in position with a face portion normally standing opposite to said one end of the bar for preventing the escape of the hooked part from the bar and provided with a recess adapted upon an operative movement of the lever to receive a hooked part therein and release it from the bar, a second slide bar at a lower level than said first named slide bar for receiving the hooked part from said first named slide bar, and cam means connected with said lever actuated by a hooked part when moved from said second slide bar for giving the lever an operative stroke for releasing another hooked part from said first named slide bar.

8. A device for supporting and delivering hairpins and the like, comprising in combination a supporting bar in inclined position for supporting a plurality of hairpins so as to slide downwardly therealong and off at the lower end of the bar, a lever pivotally mounted in position with a face portion normally standing opposite to said lower end of the bar for preventing the escape of the hairpins from the bar and provided with a recess adapted upon an operative movement of

the lever to receive a hairpin therein and release it from the bar, a second slide bar in inclined position at a lower level than said first named slide bar in position to receive a hairpin from said first named slide bar, and cam means connected with said lever actuated by a hairpin when removed from said second slide bar for giving the lever an operative stroke for releasing another hairpin from said first named slide bar.

9. A device for supporting and delivering hairpins and the like, comprising in combination a metal plate supported on edge and having its upper edge inclined for supporting a plurality of hooked parts straddling the plate so as to slide downwardly therealong and off at the lower end 15 of the inclined portion, a lever pivotally mounted in position with a face portion normally standing opposite to the lower end of said inclined portion for preventing the escape of the hooked parts from said inclined portion and provided 20 with a recess adapted upon an upward movement of the lever to receive a hooked part therein so as to carry such hooked part downwardly upon the return movement of the lever, a second slide support for said hooked parts below the level of 25 said first named inclined portion in position to receive the hooked part into position thereon when released by said lever, and means carried by said lever normally standing opposite to said second slide support at a portion of its length 30 arranged so that a hooked part when slid along said second support for removal from the device gives said lever an operative upward stroke for releasing another hooked part from said first named inclined portion.

10. A device for supporting and delivering hairpins and the like, comprising in combination a supporting member in inclined position for supporting a plurality of hooked parts so as to slide downwardly therealong and off at the lower end 40 of the member and having its upper end portion bent around so as to extend toward the front for expediting the loading of the device and for having a braking effect upon the downward movement of the hooked parts at said upper end portion, and a retainer movable adjacent to the lower end of said supporting member adapted in normal position to prevent a hooked part from sliding off the support and provided with a recess adapted in a raised position of the retainer to 45 receive therein the lowermost hooked part on the support for moving said hooked part downwardly therewith for escape from said supporting member.

11. A device for supporting and delivering 55 hairpins and the like, comprising in combination a supporting member in inclined position for supporting a plurality of hooked parts so as to slide downwardly therealong and off at the lower end of the member, a guard rail mounted in slightly 60 spaced relation to said inclined support for preventing the hooked parts from becoming disarranged thereon, and a retainer movable adjacent to the lower end of said supporting member adapted in normal position to prevent a hooked 65 part from sliding off the support and provided with a recess adapted in a raised position of the retainer to receive therein the lowermost hooked part on the support for moving said hooked part downwardly therewith for escape from said supporting member.

OTTO KLOTZ.
